UNITED STATES PATENT OFFICE

ALBERT J. RUTH, OF ST. LOUIS, AND ALBERT H. BUERMANN, OF KIRKWOOD, MISSOURI

DESIGN FOR A PUMP CASING

Application filed July 11, 1932. Serial No. 44,310. Term of patent 14 years.

To all whom it may concern:

Be it known that we, ALBERT J. RUTH and ALBERT H. BUERMANN, citizens of the United States, residing at St. Louis, Missouri, and Kirkwood, St. Louis County, Missouri, respectively, have invented a new, original, and ornamental Design for a Pump Casing, substantially as shown in the accompanying drawing, in which—

The figure is a perspective view showing one side of our new design, the opposite side being a duplication of the side shown.

We claim:

The ornamental design for a pump casing, substantially as shown and described.

ALBERT J. RUTH.
ALBERT H. BUERMANN.
